UNITED STATES PATENT OFFICE

2,077,729

SHIP'S ARMOR

Ida M. Wilcox, Salt Lake City, Utah

Application April 1, 1935, Serial No. 14,093

1 Claim. (Cl. 114—12)

My invention relates to construction and has for its object to provide a new and highly efficient construction of a unit which may be used in any structural building.

5 A further object is to provide a unit of construction which has many and varied uses and which may be used either to build buildings, forts, structural steel edifices, bridges or embattlements, or which units may be used within 10 the shell of battleships to protect their hulls from explosion, torpedoes or collisions.

A still further object is to provide a construction for ships which will make the sides thereof of imperviousness to attack by submarine torpedoes, air-bombs, mines or other explosives, and which construction will turn, trap and cause torpedoes to explode with outward force rather than damaging the interior of the ship.

As to building of forts and embattlements, 20 these units are gas-proof and bomb-proof and may be so constructed as to be unimpaired by earth-quake shock or other disturbances.

My units may be adapted for either minor or major construction for small or large use where 25 strength, rigidity and protection are required. For instance, aeroplanes—both the bodies and wings may be greatly strengthened as well as enhanced in appearance and beauty; also helmets worn by men-of-war lined with small sizes of 30 these units should also prove far more protective than the ones now in use.

Armored cars may be so constructed with 35 these units as to prevent bullets from entering the cars, or war-tanks could be made more impervious to enemy bullets by their use.

These objects I accomplish with the units of construction shown in the accompanying drawing in which similar numerals and letters of reference indicate like parts throughout the several views and are described in the specifications forming a part of this application, and pointed out in the appended claim.

In the drawing in which I have shown uses and construction of my invention,

45 Figure 1 is a sectional view of a half of a ship, showing my units of construction erected in double layers around the hull of the ship and across the deck.

50 Figure 2 is a face view of one of the units with the deflecting plate used therein when the unit is used in constructing battlements, forts, ships, etc.

55 Figure 3 is a vertical section of Figure 2 with the rear unit shown holding a meshing of fine

spring wire to catch any projectiles, should they penetrate beyond the first row of units.

Figure 4 is a face view of the units of construction with dotted lines to indicate the next deep layer of units as they will be set for uses, such as those of Figures 1 and 3, with the back units staggered in relation to the front units.

5 Figure 5 is a perspective view of some of the units of construction as made for buildings, etc., showing their means of securing them together.

10 Figure 6 is a view of a portion of a bridge showing the use of the construction-units for bridge and structural steel work.

In the drawing in Figure 1, I have shown the hull of a vessel, as A with the deck as B, and 15 within the hull and directly under the deck, I then mount my units of defense and construction. These units of defence and construction consist of hexagonal cells or chambers 1, having the six walls shown at 2, and set on rows 20 of each other to make up a completed interlocking wall C. Back of this wall I then set up another like wall D with the positioning of the hexagonal chambers 3 in this wall staggered in relation to those in the first wall as shown by the dotted lines in Figure 4. Each of the chambers 1 and 3 are provided with end closure plates secured therein by any suitable means or welded thereonto to make the walls thereof rigid and in one piece when the chambers are all set up 25 into a wall. In the chambers 1, I then provide my deflecting members which consist of a plate 5 having the center thereof curved with the edges 6 flanged outwardly to tend to catch any projectile which might penetrate the hull of the 30 ship and deflect it toward the side wall of the chamber and of the next adjoining chamber.

The deflecting plates 5 are held in the front 35 end of the cells or chambers 1 by spiral springs 8 with the large end of the spiral against the rear wall 9 of the chamber and the small front end of the spring secured to the back side of the plate 5. Stop lugs or bosses 10 are fastened through the walls of each chamber penetrating 40 into the chamber sufficient distance to stop the recoil of the plate 5 from going too far back into the chamber therefore giving a greater tendency to turn the projectile or torpedo. In the hexagonal chambers 3 I then provide a complete filling of spring material 12 such as coil 45

spring wires or fine copper or steel wires forced into the chamber in any manner of form but having sufficient spring thereto to enmesh a projectile which might have penetrated the first row or wall of cells and through the back wall 50 55

9 of the chambers 1 and the front wall 14 of the chambers 3. Thus the springing action of this material will completely stop the projectile from passing through this chamber. It is also 5 thought that some material may be used within the cells or chambers 3 which will have an effect such as will put out fires or having sufficient constituency and stiffness as to cause the projectile to further slow up and when exploded 10 this material will decrease the power of the explosion. A suitable material for this use is oil treated clay, such as modeling clay which will harden quickly when wet and which will not burn readily.

15 In Figures 5 and 6 of the drawing I have shown the use of the units of construction with Figure 5 showing the way they are set up in interlocking or interfitting rows one adjacent the next one and with each of these units E 20 secured to its next abutting or adjoining unit by sets of rivets 15.

In Figure 6 I have shown the use of units for building a bridge structure with each unit F set to, upon and abutting the next unit and each 25 unit will be secured to its next unit by suitable means such as rivets, bolts, end plates or by welding the abutting edges together.

When these units have been set together to form the desired structure for the bridge they 30 are secured together as desired and the ends may either be sealed by any design of an artistic nature simply closed over by continuous end plates or they, the ends, may be left open giving a very pleasing appearance to the bridge. 35 The top row 18 of the units 19 is then used for the top structure of the bridge and the area 20 between each edge 21 of the units is filled in with cement or other suitable material to form the level usable surface of the bridge. The ends

of the bridge may then be provided with a suitable railing that shown being of upwardly set series of pipes 22 held in place by setting them thru the edges 21 of the top row of cells and then pouring the surface cement in place holding the pipes as shown and a stringer 24 may be secured from one to the other if desired. 5

As will be obvious this type of bridge construction will be strong and rigid and should cross lines of wires, power lines, or water pipes 10 being required to cross the bridge they may be set through any row such as the top row 18 of the units 19 or the next row 25 of the units and the units will support the pipes or cables in a very satisfactory manner. This type of 15 construction will eliminate a great amount of pile driving and engineering work.

Having thus described my invention I desire to secure by Letters Patent and claim:—

In a device for protecting ships, the combination of a layer of rows of hexagonal hollow units set one onto the other to form a completed lining for the ship; another layer of like units set adjacent the ends of the first row with the units staggered in relation to the first row and with the ends of all units sealed closed; helical springs mounted in the outside layer of units one in each unit with the large end of the spring inwardly toward the hull of the ship; curved deflector plates mounted onto the outer ends of the springs said plates having the outer rims curved outwardly; stopper lugs mounted in said units to retard the backward movement of the deflector plates when struck by a projectile; and resilient absorptive material carried in the inner row of units to dampen the explosive effects of a projectile and retard the inward movement thereof. 20 25 30 35

IDA M. WILCOX.
